UNITED STATES PATENT OFFICE.

EDWIN A. ROONEY, OF FAIRHAVEN, MASSACHUSETTS, ASSIGNOR TO THE WHITIN MACHINE WORKS, OF WHITINSVILLE, MASSACHUSETTS, A CORPORATION OF MASSACHUSETTS.

COILER-FRONT FOR CARDS.

1,189,740.

Specification of Letters Patent.

Patented July 4, 1916.

Application filed October 31, 1913. Serial No. 798,392.

To all whom it may concern:

Be it known that I, EDWIN A. ROONEY, a citizen of the United States, residing at Fairhaven, in the county of Bristol and 5 State of Massachusetts, have invented the following - described Improvements in Coiler-Fronts for Cards.

The invention is an improvement in coiler front apparatus for divided cards, whereby 10 each of the many subdivisions of the card fleece can be uniformly and practicably condensed and coiled in individual sliver cans from which cans they can be run directly into a slubber or coarse roving frame with- 15 out intermediate doubling or drawing.

While the invention and particularly certain features thereof can be used with divided cards producing only four divisions of its fleece, it is more particularly adapted 20 for use with cards producing eight or more divisions or fleece sections.

In certain respects the invention is an improvement on the structure disclosed in application Serial No. 740,971, filed January 25 9th, 1913, by Elwin H. Rooney, the object being to simplify and enhance the convenience of use of said structure through a certain method of grouping or arranging the sliver cans and the distributing and coiler 30 mechanism, as hereinafter set forth, so that the operator may more conveniently reach the said cans as well as the doffer and delivery mechanism of the card without disturbing the uniformity of treatment which 35 each sliver must receive.

In the accompanying drawings, Figure 1 is a top plan view of a portion of a divided card with one form of the invention applied thereto. Fig. 2 is a side elevation of Fig. 1. 40 Fig. 3 is a top plan of a modified arrangement. Fig. 4 a side elevation of Fig. 3. Fig. 5 is a top plan, with parts in section, of the can stands for the form of Figs. 1 and 2. Fig. 6 is a similar view of the can stands of 45 the form shown in Figs. 3 and 4. Fig. 7 is a section through the table surface and calender rolls of either form.

The doffer cylinder marked 1, may be regarded as the doffer of any suitable card 50 adapted to produce a fleece in the form of numerous narrow strips or ribbons, herein termed fleece sections. For this purpose the cylinder in the present case is divided by a series of tapes 2, which divide the fleece 55 formed thereon into a plurality of fleece sec-

tions, eight in number in the machine illustrated. These fleece sections are removed from the cylinder by an oscillating doffer comb 3, which, as observed in the drawings, operates at the front side of the cylinder so 60 that any dirt it liberates may fall to the floor and not on the cylinder. As the present invention is largely concerned with the economical working of cotton waste containing more or less dirt, the advantage of locating the doffer comb at this point is obvious. 65 From the doffer comb each fleece section passes immediately into one of the trumpets 4, which are mounted in a cross-plate 5, extending across the card directly in front of the comb. The cross-plate and its trumpets are set substantially at the same level as the doffer comb, so that the fleece sections are subject to the least possible attenuation in moving to the trumpets. A set of rolls 70 operates directly in front of the trumpet nozzles drawing the condensed fleece sections therethrough and delivering them from the card. In the present case these rolls are made up of a single bottom roll 7 (dotted lines Fig. 2) which is driven by a gear train 8 from the doffer wheel 9 of the card, and a set of top rolls 10 resting by gravity upon the bottom roll and held in place thereon by means of the crotch supports 11. All the 75 top rolls 10 are of the same weight and each serves two adjacent fleece sections, pressing equally upon each of them. A weighted clearer 6, (Figs. 1 and 2) of any suitable form is placed on the top rolls 10. This 80 clearer is omitted from three of the rolls as shown in Figs. 1 and 3. The rolls and their trumpets coöperate to condense the very tenuous and narrow fleece sections discharged by the doffer comb so as to enable 85 them to be elevated safely to the level of the entrances to the cans into which they are to be coiled. The gear train 8 on the card also drives a cross shaft 12, suitably supported in brackets 12^a on the overhanging ends of 90 the card frame, and which serves as the driving member for the parts of the coiler front mechanism, driving the section-conveying mechanism of the latter through the two inclined shafts 13 and the coiler apparatus through the two upright shafts 14, both of which are bevel geared to said cross shaft 12 near its center.

The coiler front mechanism according to this invention is divided into two or more 110

sections which may be symmetrical duplicates of each other, as shown, and each division consists of a distributing mechanism or table structure set on legs resting on the 5 floor or otherwise supported in front of the card so as to accommodate a group of one-half or one-third, or a portion, of the total number of sliver cans, beneath it. Said structure is elevated above the level of the 10 doffer and delivery means of the card so as to accommodate cans of large capacity and standard diameter and each is also equipped with a series of pairs of calender rolls or other means for elevating the fleece sections, 15 from the level of the condensing mechanism, to the level of the cans and conveying and depositing them in the latter, as well as with means for coiling the sections in the cans.

20 The calender rolls are driven by one of the shafts 13 and the coiler mechanism by one of the shafts 14. When the distributing mechanism is divided into two divisions, as in the case illustrated, they are disposed 25 in front of the sides of the card so as to leave an intermediate central space between them, in which the attendant may approach the card to attend to the piecing of the middle fleece sections or for other purposes. If 30 three or more divisions are formed, similar spaces are left between them, such spaces being either for access to the card or for removal of the cans.

In the form of Figs. 1 and 2, the table 35 structure constituting each division of the distributing mechanism is of greatest dimension fore and aft of the card and of least dimension crosswise of the card and is also somewhat wider near the card than at the 40 opposite end, so as thus to accommodate the convergence of the fleece sections, as indicated in the drawings, with the least obstruction into the space left for the operator. The top surface of the table structure is desirably smooth and at its end nearest the 45 card turns downwardly forming the apron 16 inclined toward the card delivery. The sections are drawn upwardly over this apron and along or over the upper surface of the table, by means of the condensing rolls 17 and 18, which also draw the sections through the trumpets 20 in the covers 19, thereby imparting a second condensation to each section. The lower rolls 17 are carried in or 55 below openings in the table structure, on shafts 21 driven by bevel gear connections with a shaft 22, which latter gears with one of the inclined shafts 13 above referred to, being thereby driven in unison with the card. The cover 19 bearing the trumpet 20 is hinged to the table structure so that it can be turned upwardly when desired to uncover the roll opening, and the upper roll 18 is held in place on the lower roll by 60 means of supports 18^a which are covered by

the cover. Both the rolls and the covers are inclined toward the card to accommodate more readily the entrance and passage of the section into the cans beneath. The can for each fleece section is disposed immediately beneath its pair of rolls 17 and 18 but off center therefrom and is arranged to be rotated so as to cause the incoming sliver sections to be coiled therein. Such rotation may be effected by rotating the stands on 75 which the cans rest or in any other suitable way by which the sections will be coiled in the cans so as to prevent snarling when removed.

Fig. 5 shows a can stand for the form of 80 Figs. 1 and 2, 23 being an inclosing casing which can be secured to the floor between the legs of the table structure, and 24 being the individual can stands, each secured to a gear 25, the set of these gears being inter- 85 geared by idlers 26 and driven by a gear train 27 from the upright shaft 14 above referred to, the lower end of which is stepped within said casing. As thus arranged the can stands 24 are driven by the card at a 90 uniform rate of speed and each can rotates eccentrically to the calender rolls 17 and 18. The distributing mechanism of this form is shown as accommodating four cans arranged in a single row extending away from, and 95 parallel with the card. Additional cans may be added to the row as desired, the manner of grouping remaining the same.

Referring to Figs. 3 and 4, the card structure will be understood to be the same as 100 that of Fig. 1, being designated by the same reference characters. The sections of the distributor and coiler mechanism each comprise a table structure 28 mounted on legs as in the preceding case but adapted to accommodate a double, instead of a single row 105 of sliver cans thereunder. The upper surface of this table structure is also provided with an inclined apron 29, like the apron 16, of the form first described and is also slightly wider near the card than at its opposite end to accommodate the convergence 110 of the fleece sections. The calender rolls 17 and 18 with their covers 19 and trumpets 20 are the same as the corresponding parts in 115 the other form, but are arranged two abreast, so that every other fleece section may move to the calender rolls nearest the card and the alternate sections to the rolls farthest from the card. The driven rolls of each 120 pair of rolls are mounted on a common shaft 30 beneath the table which is driven by the card through an inclined shaft 13. The sliver cans are set on rotary stands 31, the same as the stands 24, but arranged in a 125 double row, extending away from the sides of the card and inclosed in a similar casing 32, intergeared by idlers 33 and driven by a train 44 from the upright shaft 14. The space between the table structures and their 130

can stands permits access to the card in the same manner as in the case of the form first described.

It will be observed that whether the cans 5 are grouped in single or double rows, the space between groups will be sufficient not only to admit the attendant but also wide enough to permit him to remove or inspect any one of the cans without touching or disturbing the others.

I claim:

1. Carding apparatus of the kind described comprising in combination a divided card, delivering fleece sections suitable for 15 direct supply to the slubber, a plurality of cans adapted to receive the separate fleece sections therefrom, such cans being disposed in groups of two or more adjacent the front of the card, means for supporting the fleece 20 sections in transit from the card to the cans, such means being divided into two or more divisions separated to provide access to the card between them, and means for coiling the sections in the cans.

2. Carding apparatus as described, comprising in combination a divided card provided with means for individually condensing the divided fleece sections issuing therefrom, a plurality of sliver cans disposed in 30 groups in front of the card, each can receiving one of the sections, means for conducting the sections upwardly from such condensing means to the cans of both groups, said means being divided into divisions horizontally 35 spaced from each other and permitting access to said delivery means between the cans, and means for coiling the fleece sections in the cans.

3. Carding apparatus of the kind described comprising a divided card having means for separately condensing the divided fleece sections issuing therefrom, a plurality of sliver cans arranged in groups adjacent such condensing means, separated means for 45 conveying the sections upwardly from the condensing means and depositing them at a higher level into the cans of said groups, and means for rotating the cans of said groups whereby such sections are coiled in 50 their respective cans.

4. Carding apparatus of the kind described, comprising a divided card, delivering fleece sections adapted for direct supply to the slubber, a plurality of sliver cans disposed at a common level, two means for distributing the divided fleece sections into their respective cans, the said distributing means being horizontally separated to provide access to the card between them, and means 55 for rotating the cans to coil the fleece sections therein.

5. Carding apparatus of the kind described comprising a card having means for subdividing its fleece into a plurality of sections, two table structures disposed in front

of such card each adapted to accommodate a group of sliver cans, means included in each table structure for distributing the sections thereon into their respective cans and separate driving connections between said structures and the card.

6. Carding apparatus of the kind described comprising a card having means to subdivide its fleece into many sections, a distributing table having apertures for the discharge of the fleece sections, a power-driven roll associated with each aperture, a removable roll superposed on each of said driven rolls, supports for said removable rolls, inclined covers covering said apertures, rolls 80 and said supports, and provided with trumpets adapted to lead the slivers into said rolls, and a sliver can beneath each aperture.

7. Carding apparatus of the kind described comprising a card having means for 85 sub-dividing its fleece into a plurality of fine sections and a drive member journaled at the front of the card, and a corresponding number of sliver cans, in combination with two section-distributing means horizontally 90 spaced from each other, both having elements driven by said drive member including conveyer members for the fleece sections, and a group of rotary stands for the sliver cans which receive such sections.

8. Carding apparatus of the kind described, comprising a card having means to subdivide its fleece into many sections, two tables supported on legs in front of the card and adapted to accommodate a group of 100 sliver cans thereunder, card-driven calender rolls mounted on said tables and adapted to move the sections therealong and discharge the same in their respective cans and means for rotating the cans beneath the said calender rolls to coil the sections therein.

9. Carding apparatus of the kind described comprising a card having means to subdivide its fleece into many sections and a table structure adapted to receive the sections issuing therefrom, said structure having an upper surface that is wider at its end near the card, means for conducting the sections convergingly along or over such surface, and sliver cans beneath such surface for 110 receiving the sections as discharged therefrom.

10. Carding apparatus of the kind described comprising a card having means to subdivide its fleece into many sections, a distributing table having apertures for the discharge of the fleece sections, and rolls mounted in registry with the apertures, in combination with inclined covers and trumpets over said apertures, a sliver can beneath each 120 aperture and means for rotating the cans.

11. Carding apparatus of the kind described comprising a card having means to subdivide its fleece into a plurality of sections, a plurality of sliver cans for such sec- 130

tions arranged in rows extending away from, and parallel with, the sides of the card and providing an entrance space between such rows, means for distributing a portion of the
5 fleece-sections to the sliver cans in each row, and means for coiling the sections therein.

In testimony whereof, I have signed this

specification in the presence of two witnesses.
